CLAIM

The ornamental design for a link chain zipper, as shown and described.

DESCRIPTION

FIG. 1 is top perspective view thereof;

FIG. 2 is bottom perspective view thereof;

FIG. 3 is a right side view thereof;

FIG. 4 is a left side view thereof;

FIG. 5 is a front view thereof;

FIG. 6 is a back view thereof;

FIG. 7 is a top view thereof; and,

FIG. 8 is a bottom view thereof.
